Paper Corporation, New York, N. Y., a corporation of New York

Application June 24, 1939, Serial No. 85,680

Term of patent 7 years

To all whom it may concern:

Be it known that I, Abner Baron, a citizen of the United States, residing at New York city, in the county of New York and State of New York, have invented a new, original, and ornamental Design for Decorative Paper or Similar Article, of which the following is a specification, reference being had to the accompanying drawing, forming part thereof.

The figure is a plan view of a piece of paper showing my new design.

I claim:

The ornamental design for decorative paper or similar article, as shown.

ABNER BARON.
